KERF-CUTTING MACHINE

Frank A. Lindgren, Western Springs, Ill., assignor
to Goodman Manufacturing Company, Chi-
cago, Ill., a corporation of Illinois

Application January 2, 1941, Serial No. 372,846

4 Claims. (Cl. 262—30)

This invention relates to improvements in kerf-cutting machines of the room and pillar type.

One of the objects of the invention is to provide an improved feeding mechanism for machines of the character described, including a fluid coupling of the hydrokinetic type, so as to afford a more compact gearing arrangement for the machine as a whole, while providing greater flexibility and ease of control in the driving connections between the electric motor and the feed cable. A further object is to provide a fluid coupling connection between the electric motor and the drive coupling for the truck, used for transporting the kerf-cutting machine from place to place in the mine.

A still further object of the invention is to provide an improved and simplified form of retarding device to take the place of a separate tail rope cable and drum heretofore commonly employed on kerf-cutting machines. For this purpose, I provide a fluid operated braking mechanism adapted to engage the ground adjacent the rear end of the machine, and adjustable longitudinally of the machine so as to counterbalance the pulling effect of the feed rope while the machine is being fed laterally along the mine wall for cutting.

Other objects of the invention will appear from time to time as the following description proceeds.

The invention may best be understood by reference to the accompanying drawings, in which

Figure 1 is a fragmentary plan view of a mining machine constructed in accordance with my invention, with parts broken away to show interior details thereof;

Figure 2 is a side elevation of the machine shown in Figure 1, mounted in transporting position on a truck, with parts broken away to show certain gearing details;

Figure 3 is an enlarged detail section taken on line 3—3 of Figure 1;

Figure 4 is a detail section drawn to a still larger scale than Figure 3, taken on line 4—4 of Figure 1;

Figure 5 is a plan view of the planetary gear mechanism, showing details of the gear shifting mechanism in section;

Figure 6 is a longitudinal section taken generally on line 6—6 of Figure 1;

Figure 7 is a fragmentary plan view showing the rear end of the machine and its driving connections with its truck when mounted on the latter as shown in Figure 2;

Figure 8 is a detail section taken generally on line 8—8 of Figure 1, showing details of the retarding device, and showing the latter in raised or retracted position;

5 Figure 9 is a transverse detail section of the retarding device, showing the latter in lowered or extended position;

Figure 10 is a plan view showing the mining machine in different angular positions relative 10 to the working face of the mine while cutting, and illustrating the operation of the retarding device under varying conditions.

Referring now to details of the machine shown in the drawings, the invention is shown as applied to a room and pillar machine including a cutter bar 10 having a cutter chain 11 thereon and mounted as usual to extend from the front end of the machine frame 12 between a base plate 13 and an electric motor 14. The base plate 13 with side walls 15, 15 forms a cuttings discharge passage extending beneath the motor 14 and a gear casing 16 at the rear end of the machine. The cutter chain extends about a driving sprocket 17 on upright shaft 18 having suitable bearing in the gear casing 16. The electric motor 14 has suitable driving connection with the sprocket shaft 18, as by a pinion 19 on motor armature shaft 20 meshing with a gear 21 on longitudinal shaft 22 having suitable bearing in the gear casing 16. A bevel gear 23 on shaft 22 meshes with a bevel gear 24 having a hub 25 loosely mounted on the sprocket shaft 18 as by anti-friction bearings 26, 27 (see Figure 6). A sliding clutch member 28 of suitable form is mounted on hub 25 and has jaw teeth 29 adapted to engage a ring 30 fixed on the sprocket shaft. With the gearing arrangement described, the cutter chain can be declutched or clutched at will to be driven directly from the electric motor in the usual manner.

The machine is adapted to be transported from one cutting place to another on a truck indicated generally at 32 in Figures 2 and 7. Said truck has a platform 33 with guide rails 34, 34 at opposite sides mounted on a base frame 35 having front and rear axles 36, 37 with supporting wheels 38, 39. The truck is designed to be driven from the electric motor 14 of the mining machine through a coupling mechanism indicated 45 generally at 40, supported at the rear end of the base frame 35 of said truck and adapted to be detachably coupled to the motor 14, as will hereinafter more fully appear.

Referring now more particularly to the flexible 50 feed mechanism and its fluid coupling connection

with the electric motor, which constitute one of the novel features of my invention, a feed rope drum 42 having a rope or cable 43 wound thereon is mounted as usual at one side of the machine so that the rope can either be trained forwardly about a guide sheave 44 at the front end of the machine, for feeding the cutter bar laterally to the coal, or be trained rearwardly about guide sheave 45 and thence about a third guide sheave 46 disposed at the rear and centrally of the machine, for maneuvering the machine over the mine floor or drawing it upon the mine truck, as required.

In the form of feed rope drum mounting shown herein, the drum 42 is loosely mounted on a hub 48 of an internal gear member 49 which in turn is rotatable on a stud 50 mounted on and projecting outwardly from the side of gear casing 16. Said drum 42 can be clutched at will to the gear member 49 by a suitable clutch, herein consisting of a pin 51 of the usual form, carried by the drum and adapted to be engaged in any one of a series of holes 52, 52 formed in the face of said internal gear member. The pin 51 is operated as usual by a handle 53.

The internal gear member 49 is driven by a pinion 54 on shaft 55 extending through the gear casing 16 and having a worm gear 56 thereon meshing with worm 57 on longitudinal shaft 58. The worm and worm gear just mentioned are preferably of the self-locking type, so that the drum 42 can be held against unwinding by pull on the rope 43, for purposes that will hereinafter be explained.

The worm 57 is driven from the gear reduction device indicated generally at 59, which in turn is connected to a fluid coupling of the hydro-kinetic type indicated generally at 60, having its impeller driven by the motor at approximately the relatively high speed of the latter.

The gear reduction device 59 herein shown consists of a two speed planetary of a general type heretofore commonly employed in kerf-cutting machines, including a sun gear 61 keyed on shaft 62 leading from the fluid coupling and meshed with a planetary gear 63 on shaft 64 (see Figures 4 and 5). A second planetary gear 65 of slightly larger pitch diameter is rotatable with said planetary gear 63 on shaft 64. The latter shaft is mounted at opposite ends in rings 66, 66 forming part of a cage 70, as will presently appear.

As is usual with planetary devices of the type herein employed, two or three similar sets of planetary gears 63 and 65 may be provided, but only one such set need be shown and described herein. The planetaries 63 and 65 are meshed respectively with internal gears 67 and 68, rotatable independently of each other. The internal gear 68 has a hub 69 keyed on shaft 58.

The cage 70 has a shell 71 surrounding the internal gear 68, a hub portion 72 rotatable on the hub 69 of said internal gear, and an inner frame member 73 (see Figure 5) of which the end rings 66, 66 form a part. The peripheral portion 74 of the internal gear 67 has bearing in a recess 75 formed in the adjacent margin of cage 70.

The shell 71 of cage 70 and adjacent periphery 74 of internal gear 67 have external gear teeth 76 and 77, respectively, of equal pitch diameter extending thereabout, and adapted to be selectively engaged by a toothed stop block 78 on shifter rod 79 so as to restrain rotation of cage 70 or internal gear 67. The shifter rod 79 is mounted in brackets 79a, 79a for manual operation in any suitable manner.

It will now be observed that when the cage 70 is held against rotation, shaft 64 with planetary gears 63 and 65 are likewise held against rotation about the sun gear, but said planetaries are free to rotate on their own axes to advance the internal gear 68 at relatively low speed. On the other hand, when the internal gear 67 is held against rotation, the planetary gears 63 and 65 rotate with the cage 70, and advance the internal gear 68 at relatively high speed. The shifting of stop block 78 from gear teeth 76 on the outer shell of cage 70 to gear teeth 77 on the outer periphery of the gear 67, or vice versa, provides an instantaneous, positive change in gear ratio in the planetary.

The form of fluid coupling 60 herein shown is of the scoop controlled type heretofore used in the application of power to various kinds of machinery. This scoop type of coupling affords certain advantages, principally that of manual control, in its present application to a kerf-cutting machine, but it will be understood that many of the advantages of a fluid coupling can be obtained by other well known types such as pump filling, or traction (constant filling) couplings, or variations thereof.

The fluid coupling shown herein consists primarily of an impeller 81, runner 82, and enclosed cover or casing 83, rotating with the impeller. The impeller is keyed to shaft 85 which is driven by motor 14 through gear 86, idler gear 87 and gear 21 on the longitudinal drive shaft 22. The last named gear is driven by the armature pinion 19, previously described in connection with the cutter chain drive gearing. The runner 82 is keyed to shaft 62 leading to the planetary gear device 59. Rotation of the impeller 81 at high speed causes the usual circulation of oil between vanes 81a and 82a formed in the opposed faces of the impeller and runner, respectively.

The amount of oil in the working circuit to vary the output speed or completely declutch the unit, is controlled by the adjustable scoop tube 88. Said tube is mounted eccentrically at one end of the casing 83 and is pivoted so it can be swung into and out of the annular ring of oil held by centrifugal force against the outer rim of said casing. When the scoop tip is in its outermost position as shown in Figure 4, it picks up the oil in the outer casing and carries it through cored openings 89 in a manifold 90 and into the working circuit inside of an inner casing 91 and between the impeller and runner, to transmit maximum power.

When the scoop is set in retracted position (shown in dotted lines in Figure 3) it is out of the annular ring of casing oil and carries no oil to the working circuit. Leak-off nozzles 92 around the rim of the inner casing 91 allow a constant escape of oil from the working circuit to the outer casing, and as no replacing oil is received from the scoop tube when in retracted position, the working circuit will be emptied and further power transmission will cease.

Adjustment of the scoop tube in intermediate positions determines the amount of oil in the working circuit and varies the resulting output speed and power.

The scoop tube 88 is preferably of the two way type, that is to say, it has two ducts at the end thereof, with their tips facing in opposite directions, so as to be operable in either direction of rotation of the fluid coupling. The scoop tube is adjusted as usual by a lever arm 84 having a toothed segment 93 thereon which may be manu-

ally operated by a control shaft 94 having a pinion 94a meshed with said segment.

The shaft 58 which drives the feed drum 42 from the fluid coupling and planetary gear as hereinbefore described, is also extended through the rear end of the gear casing 16 and has a socket member 95 thereon for detachable driving connection with the coupling mechanism 40 of the truck 32, as shown in Figures 2 and 7.

The truck coupling mechanism 40 comprises a coupler rod 96 having an irregular shaped head 97 adapted to fit in the socket 95 on drive shaft 58, and also having a squared rear end portion 97a slidably mounted in bevel gear 98. Said bevel gear is supported in the front wall of gear housing 99 carried upright on bracket 100. The bevel gear 98 is meshed with bevel gear 101 keyed on transverse shaft 102. The latter shaft has a chain sprocket 103 at its outer end, about which a drive chain 104 is trained. The drive chain extends downwardly under a pair of idlers 105, 106 and thence forwardly about a drive sprocket 107 on the rear axle 37.

The transverse shaft may also have a friction brake band 108 of the usual kind thereon, for use when the truck is being propelled along the mine tracks.

The coupler rod 96 is held in coupling position by a yoke 110 detachably engaged at opposite ends to the rear wall of the gear housing 99 by pins 111, and having a centrally disposed bearing member 112 adapted to engage an enlargement 113 on the rear end of said coupler rod. The arrangement is such that the yoke 110 can be disengaged at either end and swung away from the housing 99, and thus permit the coupler rod to slide rearwardly out of coupling position with the socket 95.

It will now be understood from the foregoing description that the drive connections from the motor to the feed drum and the truck, including the fluid coupling, affords several novel advantages peculiar to room and pillar types of kerf-cutting machines, and in addition to the low starting torque and flexibility of drive which are characteristic features of a fluid coupling.

It will be understood that in ordinary cutting operations the cutter bar is fed to the coal at a predetermined speed suitable for average cutting conditions, but from time to time unusually hard cutting conditions are encountered, often while making a single cross cut. A fluid coupling in the feed drive, as herein disclosed, provides an automatic slip or reduction in torque transmitted to the feed drum so as to reduce the feeding speed, without reducing the torque transmitted from the motor directly to the cutter chain. In fact, since the torque transmitted to the feed drum may be substantially reduced, due to the slowing down of the motor under unusually hard cutting conditions, the power available for transmission to the cutter chain will be correspondingly increased. Thus the cutter chain can usually work its way through hard places at temporarily reduced feeding speed, and the machine will immediately resume its normal feeding speed as soon as cutting conditions are again normal, with no attention from the operator.

It will be observed that the fluid coupling operates to provide the desired slip or speed reduction above set forth, with much greater uniformity, and without the loss of power that is incident to slip friction devices of the kind heretofore employed in kerf-cutting feed mechanism. A fluid

coupling can be depended upon to provide a predetermined gradual change in slip corresponding to its operating speeds, whereas with ordinary slip friction devices it is usually necessary to build up the torque to a relatively high slipping point, whereupon it will suddenly become released. Moreover, in such devices, the amount of torque to promote slippage, and the amount of slippage finally resulting, is always more or less variable and unpredictable.

Another advantage of the feed gearing arrangement herein disclosed is greater compactness especially in vertical dimensions, that is made possible by the use of the fluid coupling. Probably the most efficient and compact form of reduction gearing heretofore used for feed gearing is a two speed planetary gear device with a slip-friction control on one or both speeds. The friction control is usually by band brakes, to protect the gearing from excessive strains or shocks as well as to vary the speed of drive. Such friction controlled planetary gear is usually disposed near the end of the feed drum gear train and must be of substantial overall diameter in order to afford the required gear reduction and peripheral friction braking surface.

It will be observed that the use of the fluid coupling eliminates the necessity of friction bands or the like on the planetary gear reduction, in the form shown herein, high and low speed members 67 and 70 being positively engaged by the stop block 78, so as to produce an instantaneous change in gear ratio, instead of being frictionally controlled, as heretofore, by brake bands. In this way, the change in gear ratio can be accomplished much more readily and positively than in prior machines in which it takes an appreciable amount of time, as well as skill and energy, to adjust the friction bands manually to the proper tension.

It will also be observed that owing to the self-locking worm and worm gear disposed between the planetary gear and the feed drum 42, as herein disclosed, the feed drum will be held from unwinding while the planetary is being shifted from one speed to the other. This feature is especially desirable when the machine is being dragged over sloping ground, and it is undesirable to loosen the rope 43 relative to its anchor while changing speeds. Moreover, with the fluid coupling interposed between the planetary and the motor, the change in speed can be quickly made without stopping the motor, simply by de-clutching the coupling temporarily.

Referring now to the novel form of retarding device, a depressible brake member 115 is mounted at one side of the machine opposite the feed drum 42 in position to be extended into and out of engagement with the ground. In the form shown, said brake member comprises an elongated metal shoe 116 cooperating with a superimposed casing 117 to form a generally cylindrical housing for a fluid expansible chamber 118 of rubber or similar flexible material. Studs or bosses 116a on the bottom face of the shoe will increase its retarding effect.

The casing 117 is rigidly mounted on a plate 119 which is slidably supported between a pair of guides 120, 121 disposed along the side wall 125 of the cuttings discharge passage, as clearly shown in Figures 3 and 9, so that the entire brake member is adjustable longitudinally of the machine by means of a rod 122, rotatably supported at its rear end in a bracket 123 in position to be engaged by a suitable turning tool (not

shown), and having threaded engagement in an ear 124 integral with the casing 117. The shoe 116 is guided for vertical movement relative to the casing 117 by a pair of longitudinally disposed pins 126 carried at the inner side of the casing, and engaging in slots 127 at the adjacent side of the shoe (see Figure 9). The shoe 116 also has suitable retracting means, herein consisting of tension springs 128, 128 connected between the shoe and casing at each end of the device, as shown in Figure 8.

Fluid is introduced into the expandable chamber 118 by a pipe 131, leading through a boss 132, which is slidably engaged in a slot 133 extending longitudinally of the housing 16, as shown in Figures 8 and 9.

Fluid pressure is supplied to the chamber from a hydraulic pump 135 of any suitable form which herein is shown as being continuously driven by the electric motor through a pinion 136 on drive shaft 22. The high pressure pipe 137 leads from the motor to a three way control valve 138, and from thence, pipe 131 goes to the expandable chamber, and a second pipe 139 goes to tank 140. A relief valve 141 is also connected directly between pipe 137 and tank 140. The low pressure side of the pump is connected to the tank 140 by pipe 142. The arrangement is such that by opening valve 138 to pipe 131 the pressure in chamber 118 will expand the latter downwardly and depress the shoe 116 into braking engagement with the ground. By throwing the control valve 138 in a second or inoperative position, the pump will be unloaded through pipe 139 to the tank. In said inoperative position the pipe 131 also has connection through pipe 138 to the tank to relieve the chamber 118 of operating pressure.

The retarding device above described is used in place of the tail rope drum and tail rope connections heretofore generally employed with kerf-cutting machines of the room and pillar type.

A typical example of its method of use is illustrated diagrammatically in Figure 10. As usual, the machine is shown as cutting from right to left with the feed rope 43 anchored to a fixed abutment and extended from sheave 44 at the front left corner of the machine along the working face F so as to pull the machine laterally with its longitudinal axis disposed substantially at a right angle to said working face. Heretofore, such machines have had a retarding rope or cable adapted to be trained from the rear right corner of the machine, and paid out at such retarding speed as to counterbalance the pull on the sheave 44 and thus maintain the machine at the proper angle to the working face. As is well known, the amount of retardation required varies under different conditions, and at different times, depending upon the length of the cutter bar, the hardness and speed of cutting, the frictional resistance of the base plate of the machine itself, and other factors. I find, however, that under ordinary cutting conditions, the desired retardation can be provided by my novel braking device, its degree of effectiveness being controlled by shifting the shoe 116 longitudinally of the machine to the point where the machine is maintained at the proper cutting angle. Thus, as seen in Figure 10, if the machine in moving from position A to B assumes the angle shown in position B, this is due to insufficient retardation of the rear end of the machine. This condition is readily corrected by moving the retarding device 115 rearwardly, to a position as shown in position

C, so that the machine will again assume its proper cutting angle to the working face. Thus the retarding device is entirely self-contained and eliminates the setting of an additional jack for the tail rope, and the delays incident to the manipulation of the tail rope itself.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In combination in a kerf-cutting machine, a motor, a chain-carrying cutter bar, a sprocket for said chain, and positive geared connections between said motor and said chain sprocket, flexible feeding means for said cutter bar including a winding member, a hydrokinetic fluid coupling driven by said motor, a plural speed gear mechanism driven by said fluid coupling having positive change speed means, and self-locking worm gears driven by said gear reduction mechanism, and operatively connected to said winding member to hold the same from unwinding while said gear shift means is being operated to change the speed ratio of said gear mechanism.

2. In combination in a kerf-cutting machine, a motor, a chain-carrying cutter bar, a sprocket for said chain, and positive geared connections between said motor and said chain sprocket, flexible feeding means for said cutter bar including a winding member, a hydrokinetic fluid coupling driven by said motor independently of said chain sprocket drive having manually controllable means for varying the torque transmitted thereby from zero to maximum at working speeds of said motor, and gear reduction mechanism between said fluid coupling and said winding member including a plural speed planetary gear having positive change speed means.

3. In combination in a kerf-cutting machine, a motor, a chain-carrying cutter bar, a sprocket for said chain, and positive geared connections between said motor and said chain sprocket, flexible feeding means for said cutter bar including a winding member, a hydrokinetic fluid coupling driven by said motor independently of said chain sprocket drive, a plural speed planetary gear device driven directly from said fluid coupling and operatively connected with said winding drum, said planetary gear device including two rotatable reaction members having positive selective stop means therefor, and operative connections between said planetary gear and said winding drum including self-locking worm gears, to hold said winding drums for unwinding while said positive stop means is being operated to change the ratio of said planetary gear device.

4. In combination in a kerf-cutting machine, a frame, a motor on said frame, flexible feeding means including a winding drum, a truck for transporting said kerf-cutting machine having drive coupling means thereon, a common drive member on said frame for said winding drum and said truck drive coupling means and drive connections between said motor and said common drive member including a hydrokinetic fluid coupling, and a plural speed planetary gear device driven from said fluid coupling.
